Inventor:

Herbert Henry Mallott

By his Attorney: Arthur Gadd.

UNITED STATES PATENT OFFICE.

HERBERT HENRY MALLOTT, OF GRIMSARGH, NEAR PRESTON, ENGLAND, ASSIGNOR
TO TEXTILE UNDER-CLEARERS LIMITED, OF PRESTON, ENGLAND.

UNDERCLEARER FOR THE ROLLERS OF YARN PREPARING, SPINNING, AND LIKE
FRAMES.

Application filed January 17, 1929, Serial No. 333,065, and in Great Britain March 30, 1928.

The invention relates to under-clearers for multiple roller systems, such as draft rollers employed in ribbon lap machines, draw frames, slubbing frames, spinning mules and the like yarn preparing frames, and has for object the provision of a clearer device of an effective character below the bottom rollers of the roller system involved.

The invention involves the use of a flat clearer presenting a plane or a number of plane areas to the rollers above the same, and which member may be covered with a soft material such as flannel as is understood. By contact with the peripheries of the rollers referred to it operates to clean or clear the same in manner well known. It has imparted to it a reciprocatory motion, combined with an oscillatory motion.

According to my invention, a clearer roller is provided in spring connection only with said flat clearer, which springs form bearings for the axle of said clearer roller. The clearer roller being moved by said flat clearer and connected by springs thereto, thus rolls round a peripheral part of the roller it is in contact with, and so effectually operates thereon.

The flat clearer is held up against the rollers it is to clean by means of spring pressure.

With reference to the accompanying drawings, giving an example of the application of the invention to the roller system for a spinning mule, Fig. 1 is a plan view of a portion of Fig. 2, and the latter is a side sectional view of a roller stand and rollers thereon, suitable for use in said spinning mule, and provided with means according to my invention. *a* is a portion of the roller stand named, provided with top rollers *b*, and bottom fluted rollers *c*. *d* is what is here referred to as the flat under-clearer, and shown with inclinations at the upper face, said face being assumed suitably covered with soft material such as flannel, and for making contact with the rollers *c* above.

In the present example, said flat under-clearer is supported or held up against the rollers immediately above by means of springs such as *e*, upon which it rides. It is here also capable of an oscillatory motion on said springs. That is to say, said sliding or

reciprocatory movement is brought about by connected rod *h* pivotally connected to a projection *i* from the flat under-clearer *d*. The other end of *h* is in connection with a crank arm *k* shown attached to a shaft *m*, which latter may be freely mounted in bearings in the frame or headstock of the mule, and not shown. The operation of the shaft *m* may be attained by a lever *o* and connection *n* worked from an eccentric in connection with the back-shaft of said mule. Such an arrangement for operating the mechanism is given merely as an example of the same. It will be seen that under the conditions of working referred to, the under-clearer *d* will have imparted to it a reciprocatory motion, as well as a rocking or oscillatory motion as indicated by broken lines in Fig. 2, the latter motion coming about on account of the varying inclination of the upper faces of *d* bearing against the rollers concerned.

According to my invention, *r* is a front clearer-roller revolvably mounted in bearings forming parts of springs *s*, a number of which are assumed to be employed across or along the clearer *d*, and which springs are connected to the latter member, at the other ends to said bearings.

It will be seen that by the resilient connection named the clearer-roller *r* keeps in contact with the roller to be cleared immediately above it, or with material thereon, while it is moved in a reciprocatory manner by the flat under-clearer *d*. In this way, the clearer roller *r* tends to roll round, the roller it is in contact with, during said motion.

According to which edge of the clearer *d* the roller *r* is resiliently connected, so does the clearing operation vary, in effect, as is well known in the industry.

The invention would not be altered even if the roller *r* formed one of several of the same along the length of the edge of clearer *d* mounted as stated, instead of being only one to said clearer as illustrated.

I claim:—

For application to the rollers of yarn preparing, spinning, and like frames, a clearer roller revolvably mounted in bearings formed in springs, the latter connected to and pro-

jecting from an edge part of a flat under-clearer, said flat under-clearer adapted for a reciprocatory and oscillatory movement relatively to rollers with which it is in contact and whereby said clearer roller is caused to move round a peripheral part of the roller it is in contact with, as herein set forth.

In testimony whereof I have affixed my signature.

HERBERT HENRY MALLOTT.
